C. C. FARMER

LUBRICATOR

Filed April 27, 1921

INVENTOR
CLYDE C. FARMER
BY *Wm. M. Mealy*
ATTORNEY

UNITED STATES PATENT OFFICE.

CLYDE C. FARMER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

LUBRICATOR.

Application filed April 27, 1921. Serial No. 464,967.

To all whom it may concern:

Be it known that I, CLYDE C. FARMER, a citizen of the United States, residing at Edgewood, in the county of Allegheny and 5 State of Pennsylvania, have invented new and useful Improvements in Lubricators, of which the following is a specification.

This invention relates to automatic lubricating devices, and more particularly to a 10 lubricator for air compressors.

In lubricators adapted for supplying lubricant to the air cylinder of a compressor, when the filling cap is removed while the compressor is running, for the purpose of 15 filling the lubricator with lubricant, fluid under pressure and perhaps oil is liable to be blown out at the open end of the lubricator, making it disagreeable and difficult to replenish the lubricant supply.

20 The principal object of my invention is to provide a lubricator having means for overcoming the above difficulty.

In the accompanying drawing, the single 25 figure is a central sectional view of a lubricator embodying my invention.

For the purpose of illustrating one application of my invention, I have shown a lubricator of the type disclosed in Patent No. 1,337,687 of C. L. Bubb, dated April 20, 30 1920, and comprising an oil cup 1 adapted to be connected by pipe 2 to the air cylinder of a fluid compressor.

Centrally within the oil cup chamber 3 there is screwed into the base portion of the 35 cup a cylindrical plug 4, having a central bore 5 communicating with the pipe 2.

Mounted on the plug 4 is a sleeve 6, which at the lower end is slightly spaced from the

plug 4, so as to provide a restricted feed passage from the oil chamber 3, through 40 which oil is supplied by capillary attraction to a passage 7, leading to the passage 5.

The upper end of the oil cup 1 is normally closed by a filling cap 8, having 45 screw-threaded engagement with the body of the oil cup.

According to my invention, the passage 5 is diverted laterally at the upper portion of the plug 4, as shown at 9, so that when the cap 8 is removed from the oil cup for filling the chamber 3 with lubricant, if the air compressor is running, the blowing of air and possibly oil will be diverted laterally and will not interfere with the filling of the oil cup, which may readily be accomplished at 55 the side of the plug opposite the lateral outlet 9, and without danger of getting oil into the passage 5.

Having now described my invention, what I claim as new and desire to secure by Letters Patent, is:—

In a lubricator for air compressors, the combination with an oil cup casing and a removable cap having a pocket, of a plug secured within the casing and extending 65 into said pocket and having a central passage adapted to communicate with the compressor, and a lateral passage in said plug which connects the central passage with the pocket in the removable cap and through 70 which fluid and oil from the compressor is diverted to one side of the cap to permit filling of the oil cup casing at the other side.

In testimony whereof I have hereunto set my hand.

CLYDE C. FARMER.
